OP D 15,409

DESIGN.

H. HUNT.

CARPET.

No. 15,409.

Patented Sept. 16, 1884.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 15,409, dated September 16, 1884.

Application filed August 6, 1884. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The design consists in the arrangement and grouping of various figures and groups of figures, which is shown in the accompanying photograph. The face of the design is closely filled in, and the various small figures are usually repeated and arranged in groups and sub-groups. On the left upper edge of the

photograph is an oval group of small star-shaped figures inscribed in circles. The group is completed at the right center edge. In the center above is a group of small circular figures. To the right above is a figure resembling a fragment of a triple-rowed border. It is repeated in reverse on the lower part of the photograph. To the left above is a tree-like figure, which is repeated with slight modifications in various places on the design. In the center below is an oval group of circular figures. Various other smaller figures and groups of figures fill in and complete the design.

I claim—

The design for a carpet, substantially as shown and described. 35

HENRY HUNT.
